UNITED STATES PATENT OFFICE

164,761

GANG SAWMILL MACHINE

Homer A. Busbee, Ocala, Fla.

Application June 8, 1950, Serial No. 10,402

Term of patent 14 years

(Cl. D93—3)

To all whom it may concern:

Be it known that I, Homer A. Busbee, a citizen of the United States, residing at Hill Street, city of Ocala, State of Florida, have invented a new, original, and ornamental Design for Gang Sawmill Machine, of which the following is a specification, reference being had to the accompanying drawings, forming a part hereof.

Fig. 1 is a perspective view of one side of a gang sawmill machine embodying my new design; and

Fig. 2 is a perspective view of the other side thereof.

I claim:

The ornamental design for a gang sawmill machine, as shown.

HOMER A. BUSBEE.
